Primary Examiner — Cynthia M Chin(74) *Attorney, Agent, or Firm* — Carter, DeLuca, Farrell & Schmidt LLP(57) **CLAIM**

The ornamental design for a utensil handle, as shown and described.

DESCRIPTION

FIG. 1 is a perspective view of a utensil handle in accordance with the present design;

FIG. 2 is a right side elevational view thereof, the other side being a mirror image thereof;

FIG. 3 is a top plan view thereof;

FIG. 4 is a bottom view thereof;

FIG. 5 is a front elevational view thereof; and,

FIG. 6 is a rear elevational view thereof.

The broken lines shown are included for the purpose of illustrating a portion of the utensil handle that forms no part of the claimed design.
